REINFORCED RAILROAD TRACK STRUCTURE
Nelson K. Moses, Ashtabula, Ohio, and Robert A. McClung, West Palm Beach, Fla., assignors to Railroad Permanent Way Products Corp., Ashtabula, Ohio, a corporation of Ohio

Filed Jan. 21, 1966, Ser. No. 522,308
10 Claims. (Cl. 238—25)

ABSTRACT OF THE DISCLOSURE

A rail track construction of the type for supporting traction rails and including elongated concrete beams supported on a sub-graded roadbed of compacted ballast, the elongated concrete beams having jack means at least at each end for temporarily supporting the beams above the roadbed so that the beams can be properly leveled, and once the beams are leveled, the beams are encased on their sides and bottom walls by a concrete slab poured over the sub-graded roadbed.

The present invention relates to improvements in railroad track structures as well as the method of constructing the same.

More particularly, the present invention relates to improvements of railroad track structures in which pre-cast elongated concrete beams are used for supporting the track rails.

In our United States Patent 3,223,328, issued Dec. 14, 1965, there is disclosed a "Track Structure for Railroads or the Like" in which pre-cast concrete beams are utilized for supporting traction rails, the beams being tied together by cross beams of concrete. While the disclosure in the aforementioned patent provides a very capable track structure, the present invention is an improvement of such disclosure in that the construction of the track structure is simplified and reduced in costs without a loss in structural strength and, thus, the track structure is also capable of properly supporting railroad rolling stock moving at extremely high speeds, for example speeds in the order of 200 miles per hour.

It has long been an established practice in the construction of track structure to support traction rails on wooden crossties, the crossties being supported on a roadbed of ballast such as crushed stone or the like. In more detail, steel tie plates were placed between the wooden crossties and the rails and spikes were driven through the holes in the tie plates into the wooden ties with the head of some of the spikes bearing against the base flange of the rails to hold the rails upon the ties.

More recently, improvements in track construction have been made wherein rubber rail seats are positioned between rails and tie plates. Such track structure cushioned impact loads and reduced the severe and destructive wear on the tie plates and/or ties. Even further efforts have been made to form the roadbed of poured concrete defining a slab, the concrete being poured directly over a sub-grade roadbed of ballast or the like. The rails were then anchored or secured directly to the top surface of the slab of concrete.

While such prior efforts are improvements over the standard practice of supporting traction rails upon wooden crossties with steel tie plates positioned therebetween, they have not been entirely satisfactory from a structural standpoint in providing a track structure capable of supporting railroad rolling stock moving at extremely high speeds. In the situation where rubber rail seats are used in combination with rails, tie plates and ties, it will be obvious that the impact loads of high speed rolling stock will be too severe and destructive over a period of time and, thus, such a track structure would involve costly

2

everyday maintenance. On the other hand, where a solid slab construction for railroad track structure provides a better foundation support for the rails than just ties and ballast, its construction requires infinitely more workmanship and care. The surface of the slab must be finished to the exact level or contour desired and must have a smooth finish in order to properly seat the base flange of the traction rails. Holes for the track mounting bolts must be drilled with extreme accuracy using gang drills and jigs. The slightest irregularity in the finish of the upper surface of the poured slab and in the laying of the rail or in faulty workmanship in any degree results in costly repairs. If insertion of shims becomes necessary due to construction errors in the top surface of the slab, this will greatly diminish the strength of hold-down fasteners, thereby reducing effectiveness of the slab and greatly increasing costs of maintenance.

A principal object of the present invention is to provide an improved track structure and method of constructing the same which will support high speed rail traffic while obviating the structural defects of prior track structures.

Another object of the present invention, is to provide a track structure and a method of constructing the same in which the cost of initial construction is materially reduced because of quickness and ease of erecting the track structure in an accurate manner.

Another object of the present invention is to provide an improved beam construction for use in railroad track structures, the pre-cast beam construction being capable of accurate positioning in rows and leveling relative to other beams.

Still a further object of the present invention is to provide an improved track structure utilizing pre-cast concrete beams or the like having an accurate and smooth traction rail receiving surface, the beams being capable of easy adjustment both from a standpoint of level and gage and then anchored permanently in position by the pouring of a concrete slab which encases the beams on their bottom and sides.

Ancillary to the immediately preceding object, it is still a further object of the present invention to provide a track structure utilizing pre-cast elongated concrete beams for supporting the traction rails, the beams being encased in a concrete slab which includes the area between the beams being filled with the concrete so as to provide a smooth, generally flat surface across the top of the track structure thereby improving the aerodynamic flow characteristics between the bottom of railroad rolling stock and the track structure.

These and other objects and advantages of the present invention will be more apparent from the following specification, claims and drawings in which:

FIGURE 1 is a side elevational view of the track structure of the present invention prior to the pouring of the concrete slab about the elongated beams;

FIGURE 2 is a sectional view of the track structure of the present invention taken substantially on the line 2—2 of FIGURE 1, portions of the view being broken away and the view further showing the concrete slab after the same has been poured, the beams being shown with the jack bolts still therein;

FIGURE 3 is a perspective view of a gage bar for use in gaging the distance between parallel beams of the track structure shown in FIGURE 2;

FIGURE 4 is a perspective view of a finished portion of track structure made according to the present invention and illustrating the traction rails suitably anchored on the elongated beams;

FIGURE 5 is an enlarged cross-sectional view taken on the line 5—5 of FIGURE 4; and,

FIGURE 6 is a fragmentary perspective view of the

end of one of the elongated concrete beams, the view illustrating the jack means for leveling the upper surface of the beam to a predetermined level both about the longitudinal axis of the beam as well as about a horizontal axis extending transversely of the longitudinal axis of the beam.

The method of constructing the track structure according to the present invention may be broadly described as follows. Pre-cast concrete beams which may be either prestressed or poststressed as desired, are first positioned on a previously prepared sub-grade roadbed of compacted ballast such as crushed stone or the like. The beams are temporarily supported in parallel rows with their lower surface or bottom of each beam being spaced above the upper surface of the sub-grade roadbed. After the beams have been initially positioned in end to end relationship in spaced rows, the beams are then adjusted so that their upper surface has an exact and perfect level for reception of the base flange of the track rail. It will be appreciated that a resilient pad or pads may be inserted between the base flange of the traction rail and the beam. The adjustment of level may require an adjustment of the beam for height relative to height of other beams in the same row, as well as an adjustment for proper level of the upper surface of the beam about the longitudinal axis of the beam and/or about a horizontal axis transverse to the longitudinal axis of the beam. Once the beams have been adjusted for level, then the distance between beams of the rows of beams is accurately gaged and by use of tie bars the beams are bolted in place for the exact and permanent gage. In some instances, it may be desired to gage the distance between the beams of the parallel rows prior to the adjustment for level of the particular beams and the adjustment for height. Once all of the adjustments of the beams individually and in the rows have been made then a filler is compacted beneath the bottom of the beam and the upper surface of the sub-grade roadbed so as to provide a permanent support for the beam on the sub-grade roadbed, the filler being then filled up along each side of the beam to provide permanent lateral support. It will be noted, the area between opposed sides of beams in the rows is completely filled with the filler so that the filler's upper surface is substantially level with the upper surface of the beams. Preferably, the filler is concrete which is poured and compacted beneath the beam and then filled in the aforesaid manner between the rows of beams as well as the outside of the rows of beams in one pour. The concrete filler is then let to cure and set and thus form a slab with embedded beams therein. Alternatively, a ballast of crushed stone or the like may be used and filler applied in substantially the same manner.

Once the slab has been poured and set around the beams, the beams are then ready for the laying of the traction rails. The traction rails may be gaged with respect to one another in any known manner and then secured to the beams either with or without resilient pads and/or tie plates between the base flange of the rails and the upper surface of the beams. Either standard rail lengths may be used or welded rails may be used and once the rails have been gaged and then fastened or anchored to the beams, the track structure is complete and ready for use.

Referring now specifically to FIGURES 1, 2 and 4 of the drawings, the track structure of the present invention includes a sub-grade roadbed 10 which is usually prepared from ballast of crushed stone which is compacted. The sub-grade roadbed 10 has its upper surface 12 graded to the general contour desired. After the sub-grade roadbed 10 has been prepared, a plurality of pre-cast concrete blocks or pads 14 are discriminately positioned along the roadbed in the general path of the rows of pre-cast concrete beams 16. In more detail, the blocks or pads 14 are spaced apart in such a manner that there is at least one block extending under the abutting ends of adjacent beams 16 with an additional block positioned under an

intermediate portion of a beam. The blocks 14 are usually embedded into the ballast of compacted stone of the sub-grade roadbed as shown in FIGURES 1 and 2. A steel bearing plate 18 is positioned on the top of each of the blocks 14, the purpose of the plate 18 being described in more detail later in the specification.

The elongated concrete beams 16 may be either straight or curved depending upon their use in the track structure. Of course, where there is a straight section of track, the beams 16 will be straight and where it is necessary to have a curved section of track, the beams 16 will be pre-cast to the desired radius of the curves. Beams 16, which may be pre-cast at the site of construction or at a nearby plant and then shipped to the site, may either be prestressed or poststressed as desired. In fact, in some situations it may be desired not to place any particular stress on the beam either before or after casting but to only reinforce the beam.

Each concrete beam 16 is elongated and is approximately 39 feet in length made with its ends 20 flat. The beams are cast having a finished smooth upper surface 22 outwardly and downwardly sloping sidewalls 24 and 26 and a flat lower or bottom surface 28. The upper finished surface 22 of the beam 16 may be provided with a one inch in 40 inch cant or other as desired, so that the traction rails 30 when supported on the beams have a cant. The beams 16 are provided, at spaced points along each of their side walls 24 and 26, with depressions or wells 32 cast therein, the beam also being provided with a lateral hole 34 therethrough having its ends open to opposed depressions or wells 32.

At the time of casting of the beams 16, a non-circular member 35, which is interiorly threaded, is positioned within the interior of the beam, the non-circular member 35 being a nut or the like. When the beam is cast with the member 35 positioned therein, the hole through the member 35 which is interiorly threaded is aligned with a hole 36 also cast in the beam and extending through the beam from the top surface 22 to the bottom surface 28 thereof. As best shown in FIGURES 2 and 6, a pair of nuts or members 35 are positioned in the beam 16 adjacent each end thereof with holes 36 for members 35 being spaced apart laterally on opposite sides of a vertical plane extending through the longitudinal axis of the beam. A jack bolt 40 is received in each hole 36 and threaded through the member 35 so that its lower end 42 extends beneath the bottom surface 28 of the beam 16. The jack bolt 40 is provided with a head 44 on its upper end for receiving a tool (not shown) which permits the jack bolt to be rotated and moved vertically with respect to the member or nut 35. A similar arrangement of a pair of members 35 and jack bolts 40 are arranged intermediate the pairs of members and jack bolts at each end of the beam 16 as clearly shown in FIGURE 1.

Additionally, the beam 16 when it is cast may also be cast with holes 46 spaced along and in its upper surface for receiving plugs 47 into which spikes 48 may be driven to hold the traction rail 30 on the upper surface of the beam. As shown in FIGURE 5, the base flange of the rail 30 may be seated on a resilient pad 50, the pad extending completely along the length of the rail or discriminatedly at intervals along the length of the rail.

The beams 16 are positioned in substantially abutting end to end relationship and in parallel rows on the sub-grade roadbed 10 with the lower ends 42 of the jack bolts 40 engaging the steel bearing plates 18 carried on the pads or blocks 14. This provides a temporary positioning and supporting of the beams with the next step in the construction of the track structure being an accurate adjustment of the beams for gage relative one to another and for proper level of the upper surface 22 thereof. With respect to adjustment for gage, a gage bar 52 (FIGURE 3) having notches 54 therein spaced apart a predetermined gage, is placed with one of its notches engaging

the shank of the inside jack bolt 40 of the beam in one of the rows. If the opposite notch 54 of the gage bar does not engage the oppositely disposed shank of the inner jack bolt 40 of the opposite beam then the beams must be moved laterally relative to one another to a position of proper gage. The lateral adjustment for gage is accomplished by a tie bar 56 extending through oppositely disposed holes 34 in the beams. The tie bar 56 has its opposite ends threaded and it is arranged to receive nuts 58 and 60 on each side of a beam. The nuts 58 and 60 bear against steel washers or bearing plates 62 and, consequently, by suitable adjustments of the nuts 58 and 60, the beams in the rows can be moved laterally relative to one another until they attain a position of proper gage.

In order to adjust the level of the upper surface 22 of the beams 16 to a predetermined level, the jack bolts 40 are suitably rotated in a desired sequence so that the members 36 raise or lower the particular beam. If it is desired to orient the beams about their longitudinal axis, the jack bolts 40 on one side of a vertical plane through the longitudinal axis of the beam may be rotated relative to the jack bolts on the opposite side of the longitudinal axis so as to pivot the beam about its longitudinal axis. On the other hand, if it is desired to lift one end of the beam and lower the other end or vice-versa, then suitable adjustment is made to one or the other of the pairs of jack bolts in opposite ends of the beams. It will also be understood that if a particular beam needs to be elevated or lowered in its entirety, all of the jack bolts are rotated a predetermined amount to obtain the desired raising or lowering of the beam.

While the description above with regard to the adjustment for gage and for leveling of the beams has been described with the gage adjustment being made first, it will be appreciated that in certain instances it may be desirable to reverse the procedure and adjust the upper surfaces of the beam for proper level and adjust the rows of beams for proper gage.

After the beams 16 have been adjusted for proper gage and level as described above, then a filler F is compacted into the area beneath the bottom surface 28 of the beams 16 and the upper surface of the subgrade roadbed 10 and is filled up along the opposed sidewalls of the beams as well as along the outside sidewalls of the beams until it is substantially level with the top surface 22 of the beams. Preferably the filler is concrete which is poured in a single pour into the area beneath the beams as well as the area between the rows of beams and outside of the beams, the concrete being let to cure or set and thus anchor the beams in accurate position for receiving the traction rails 30. When the concrete is poured as a filler, a gutter G (FIGURE 2) can be provided in the top surface of the slab formed by the concrete, the gutter extending longitudinally of the slab between the rows of beams. Suitable outlets can be provided to the outside of the track structure for draining water or the like from the track structure.

By having the slab formed by the filler substantially level with the top surface of the beams 22, a substantially smooth surface is provided for the track structure thus enhancing the aerodynamic flow characteristics between the bottom of rolling stock and the track structure by lowering the drag created by turbulence.

While it is mentioned above that the filler F is preferably concrete, it may also be ballast similar to the ballast used in the subgrade roadbed, the ballast being compacted underneath the beams to provide good support therefor as well as between the rows of beams and on the outside of the rows of beams. The ballast will provide a strong track structure but the slab of concrete formed as a filler provides an even stronger track structure. Once the beams 16 have been permanently set in the filler F, then the jack bolts 40 may be removed from the nuts or members 35 and used on other beams. Of course, the tie bars 56 remain embedded in the filler and thus firmly anchor the

gage of the beams. The holes 36 remain after the jack bolts 40 are removed and are suitably filled with a filler such as ground rock, plastic, or the like. This prevents water draining down through the holes in the beams and possibly accumulating in the subgrade roadbed.

After the beams 16 have been anchored in the filler F and the jack bolts 40 removed therefrom, the traction rails 30 may then be laid and fastened to the beams in any suitable manner.

The novel track structure beam for use in such track structure and method of constructing such track structure described and illustrated in the drawings fully and effectively accomplish the objects and advantages of the present invention. However, it will be understood that certain modifications to either the track structure, beam, or method may be made without departing from the principles and spirit of the present invention.

Therefore, the terminology used throughout the specification is for the purpose of description and not limitation, the scope of the invention being described in the claims.

What is claimed is:

1. In a rail track construction for supporting traction rails, the combination comprising: a sub-grade roadbed 25 of compacted ballast; spaced rows of elongated concrete beams; jack means at least at each end of each of said beams for adjustably and temporarily supporting each of said beams with their lower surfaces spaced above the surface of the sub-grade roadbed; and a concrete 30 slab encasing the spaced beams on their sides and bottom walls, said slab being substantially level with the top surface of said beams.

2. A track construction as claimed in claim 1 in which each of said jack means includes a jack bolt extending 35 substantially vertically through the beam, said bolt having a lower ground engaging end extending beneath the lower surface of the beam and an upper tool engaging end extending above the upper surface of the beam, and means fixed relative to the beam for threadedly receiving 40 said jack bolt and raising or lowering the beam when said bolt is rotated.

3. A track construction as claimed in claim 2 in which said last mentioned means includes an interiorly threaded non-circular member embedded in the beam.

4. A track construction as claimed in claim 2 including a bearing plate positioned on said sub-grade roadbed for engaging the ground engaging end of said jack bolt.

5. A track construction as claimed in claim 1 in which said concrete slab includes a drain gutter in its upper surface and extending generally parallel to and between the rows of concrete beams.

6. A track construction as claimed in claim 1 including tie bars extending between and through oppositely disposed beams of the rows, each of said tie bars having its 55 ends threaded, a bearing washer on each end of each tie bar and engaging the side of one of the beams, and a nut threaded onto each of the ends of said tie bars whereby the beams in said rows may be adjusted laterally relative to one another while they are temporarily supported by 60 said jack means.

7. A pre-cast elongated concrete beam for use in supporting traction rails, said beam having a smooth upper surface for reception of the base flange of the traction rail, jack means provided at least adjacent each of 65 the ends of the beam, said jack means being capable of temporarily supporting and adjustably positioning the beam so that its upper surface is at a predetermined desired level, each of said jack means including an exteriorly threaded jack bolt extending substantially vertically through a hole in the beam and means fixed relative to said beam for threadedly receiving said jack bolt and adjustably raising and lowering the beam when said jack bolt is rotated.

8. A pre-cast elongated concrete beam for use in supporting traction rails, said beam having a smooth upper

surface for reception of the base flange of the traction rail, a pair of jack bolts extending substantially vertically through holes in said beam adjacent one end thereof, said jack bolts being spaced laterally of said beam on opposite sides of a vertical plane extending through the longitudinal axis of said beam, a pair of interiorly threaded members fixed relative to said beam for threadedly receiving said pair of jack bolts, a second pair of jack bolts extending through said beam adjacent the other end of the beam, said second pair of jack bolts being spaced transversely of said beam on opposite sides of the vertical plane through the longitudinal axis of said beam, and a second pair of interiorly threaded members fixed relative to said beam for threadedly receiving said second pair of jack bolts.

9. A pre-cast elongated concrete beam as claimed in claim 8 in which said first pair and said second pair of interiorly threaded members are each a nut embedded in said concrete.

5 10. A pre-cast elongated concrete beam as claimed in claim 8 including jack means carried by said beam intermediate said first pair and said second pair of jack bolts.
